UNITED STATES PATENT OFFICE.

FRANK M. MORTON, OF PHENIX CITY, ALABAMA, ASSIGNOR TO COLUMBUS TRUCK & SUPPLY MFG. CO., OF COLUMBUS, GEORGIA, A CORPORATION.

RAW-STOCK DYE VAT.

Application filed May 21, 1923. Serial No. 640,564.

To all whom it may concern:

Be it known that I, FRANK M. MORTON, a citizen of the United States, residing at Phenix City, in the county of Lee and State 5 of Alabama, have invented certain new and useful Improvements in Raw-Stock Dye Vats; and I do declare the following to be a full, clear, and exact description of the invention, such as will enable others skilled 10 in the art to which it appertains to make and use the same.

My invention relates to improvements in raw stock dyeing apparatus and more particularly to those of the closed vat type in 15 which the stock is supported in the vat on a perforated false bottom and is supplied with dye by means at the upper end of said vat.

One object of the invention is to provide 20 a novel form of hollow head for closing the upper end of the vat, compressing the stock and distributing the dye liquor evenly, preventing channeling thereof through the stock with resultant non-uniform dyeing.

Another object of the invention is to provide 25 a novel association of parts whereby compressed air, or water or steam, may be admitted to the vat through a portion of the dye supply pipe, for the purpose of driving 30 out surplus dye from the stock or washing the latter preparatory to dyeing.

A still further object is to provide effective means whereby the dyed stock may be quickly and easily ejected from the vat, 35 under the influence of fluid pressure.

With the foregoing in view, the invention resides in the novel subject matter herein- 40 after described and claimed, the description being supplemented by the accompanying drawings.

Figure 1 is a perspective view of a dyeing apparatus constructed in accordance with my invention.

Figure 2 is a vertical sectional view taken 45 substantially on line 2—2 of Fig. 1.

Figure 3 is a horizontal section as indicated by line 3—3 of Fig. 2.

In the drawings above briefly described, the numerals 1 designate a pair of duplicate 50 dye vats operatively associated with a dye liquor tank 2 and a circulating pump 3. I preferably provide a single cover plate 4 for application to either of the vats 1 and when this plate is applied to one vat and 55 the latter is operating, the other vat is open

for emptying and refilling, as will be clear by reference to Fig. 1.

Any suitable means may be employed for securing the cover plate 4 in place, but I prefer to provide a series of bolts 5 pivoted 60 on each vat for this purpose, said bolts being receivable in peripheral notches 6 with which said cover plate is provided.

In the construction shown, each vat 1 is provided with a solid imperforate bottom 7 65 and with a perforated false bottom 8 which is adapted to support the stock to be dyed, said vat being provided with dye outlet piping 9 which may discharge either into the tank 2 or into some other outlet, according 70 to the manner in which the valves 10 and 11 (Fig. 1) are set. The piping 9 is connected with the vat by a suitable coupling 12 having a comparatively small elbow 13 which leads from its exterior to its interior. A 75 short pipe 14 is connected with the inner end of the elbow 13 and discharges into an appropriate coupling 15 positioned between the bottom 7 and the false bottom 8, and a discharge nozzle 16 rises from said coupling 80 15 through said false bottom. This nozzle, as will be hereinafter more apparent, is intended to supply compressed air to the vat 1 for the purpose of ejecting the dyed stock therefrom.

The side wall of the vat 1 is provided near its upper end with a dye liquor inlet passage 17 to which a supply pipe 18 leads from the pump 3, said pipe being provided with an appropriate cutoff valve 19 spaced 90 a short distance from the vat. Suitable piping 20 having a cutoff valve 21, is provided for admitting water or steam into the pipe 18 between the valve 19 and the vat, when said valve 19 is closed and it will thus be 95 seen that the stock within the vat may be effectively cleansed before the dyeing process. Additional piping 22 for supplying compressed air, discharges into the piping 18 between the vat 1 and the valve 19 and 100 is provided with a cutoff valve 23 for each vat. Thus, by closing the valve 19 and opening the valve 23, compressed air may be admitted into the upper end of the tank to drive surplus dye liquor from the stock. A 105 branch pipe 24 having a control valve 25, extends from the piping 22 and connects with the elbow 13 for supplying the necessary air pressure for ejecting the dyed stock. A novel arrangement of parts is pro- 110

vided for evenly supplying the dye liquor to the stock, this construction being clearly illustrated in Figs. 2 and 3. The numeral 26 designates a horizontal plate below the cover plate 4, both of these plates being declined from their peripheral portions to their centers. The space between the edges of the two plates is intended to communicate with the passage 17 to receive dye liquor from the latter and the lower plate 26 is provided with a multiplicity of perforations 27 for evenly distributing this liquor to the stock. In the preferred form of construction, the lower plate 26 is provided with a plurality of upstanding fins 28 which contact with the cover plate 4 to space the two plates apart, said plates being relatively secured by any desired means, such as the central eye-bolt 29 passing through both of said plates. The eye of this bolt serves as means for connecting a chain hoist or the like with the hollow head formed by the two plates, for the purpose of moving the latter from one of the vats to the other, as occasion may demand.

The construction of the hollow head formed by the plates 4 and 26, is such that when this head is secured in place by the bolts 5, the stock is compressed in the vat to the proper extent to obtain the best dyeing results. This construction also serves to more evenly distribute the dye liquor to the stock, than similar arrangements heretofore provided and it is thus insured that the dye liquor shall not channel through certain restricted areas and produce uneven dyeing. It will be seen that the liquor forced downwardly through the stock will discharge through the perforated false bottom 8 and the piping 9 and that circulation may be carried on for any desired length of time by properly controlling the several valves and the pump 3. Then, to entirely drain the vat, after the period of dye circulation, the valve 23 may be opened to admit compressed air into the upper end of said vat. Thus, all surplus dye will be forced from the stock. When now the hollow head is detached from the vat, the valve 25 may be opened and compressed air admitted under the dyed stock, whereupon the latter becomes in effect, a piston and is bodily moved upwardly and ejected from the vat. The vat may be washed after the dyeing operation by admitting water or steam from the piping 20 and this water or steam is also usable for cleansing the stock before dyeing, if desired.

From the foregoing, it will be seen that I have produced an exceptionally simple and compact apparatus for raw stock dyeing, yet regardless of this simplicity, the apparatus has proven to be exceptionally rapid and advantageous. Attention may here be directed to the fact that by having the plate 26 declined from its peripheral edge to its

center, insertion of this plate into the vat 1, is greatly facilitated, as when any portion of said plate is engaged with the upper edge of the vat wall, the inclination of the plate will assist materially in sliding the entire dye-supply head toward centered relation with respect to the vat, permitting said plate to readily enter the latter. Excellent results have been produced when using the construction herein disclosed and this construction may therefore be considered the preferred form of the invention, but it is to be understood that within the scope of the appended claims, numerous minor changes may be made.

I claim:

1. A raw stock dye vat having a dye inlet through its side wall adjacent the upper end of the latter, a hollow head for reception in the upper end of said vat, said head having a perforated bottom wall declined throughout its area from its peripheral edge to its center to guide it into the vat, said head being open at its edge to receive dye from said inlet, and means for securing said head in the upper end of the vat to cause said bottom wall to hold the contents of the vat under compression while supplying dye thereto.

2. A raw stock dye vat having a dye inlet through its side wall adjacent the upper end of the latter, a cover plate for application to the upper end of said vat, a perforated plate spaced below said cover plate and adapted for reception in the upper end of the vat, said plates being declined from their peripheries to their centers, spaced upright lugs on one of said plates contacting with the other plate to space the two plates apart, means for securing said plates with respect to each other, and means for securing the edge of said cover plate to the vat wall, the space between said plates being open at the edges of the latter for communication with said dye inlet.

3. A raw stock dye vat having a removable dye supply head at its upper end, a perforated false bottom to support the stock, and a surplus dye outlet below said bottom including a coupling secured to the vat, said coupling having a fluid pressure inlet elbow from its exterior to its interior and of less size than the internal diameter of the coupling, a fluid pressure nozzle extending through said false bottom to supply pressure to eject the dyed stock from the vat, and a pipe under said false bottom connected with said nozzle and said elbow.

4. A raw stock dyeing apparatus comprising a vat having a perforated false bottom to support the stock, a perforated head for supplying dye to the stock, a dye inlet pipe leading to said head and having a cut-off valve spaced outwardly therefrom, and a dye outlet pipe from the vat under the false

- bottom, having a cut-off valve spaced outwardly from said vat, fluid pressure inlets from a common source discharging into said dye inlet and outlet pipes between the 5 vat and the cutoff valves of said pipes, and means for selectively directing the pressure either into the dye inlet pipe when its cutoff valve is closed or into the dye outlet pipe when the cut-off valve of the latter is closed.
- 10 5. A raw stock dyeing apparatus comprising a vat having a removable head for closing its upper end and supplying dye liquor to the contents of the vat, a perforated false bottom in said vat and a valved 15 outlet from said vat below said bottom, a nozzle extending through said false bottom for supplying fluid under pressure to eject the dyed stock, a pipe leading from said nozzle to the exterior of the vat, a dye liquor supply pipe at the upper end of the vat communicating with said head and having a cut-off valve spaced a slight distance from said vat, a fluid pressure line discharging into said dye liquor supply pipe between said cutoff valve and said vat, said line having 20 a control valve, and a branch air line from the first named air line to said first mentioned pipe for supplying compressed air to said nozzle, said branch air line also having a control valve. 25
- In testimony whereof I have hereunto affixed my signature.

FRANK M. MORTON.
